UNITED STATES PATENT OFFICE.

JOHN DALLAS LAW, OF DUNEDIN, NEW ZEALAND, ASSIGNOR OF ONE-HALF TO WIL-
LIAM FRANCIS JAMES, OF DUNEDIN, NEW ZEALAND.

MOTION-PICTURE-PROJECTING MACHINE.

Application filed August 31, 1921. Serial No. 497,296.

To all whom it may concern:

Be it known that I, JOHN DALLAS LAW, citizen of the Dominion of New Zealand, and resident of Dunedin, in the Provincial District of Otago, have invented certain new and useful Improvements in Motion-Picture-Projecting Machines, of which the following is a specification.

This invention relates to picture project-
10 ing machines, wherein moving films, of an inflammable nature are employed.

In operating such machines, it frequently happens that the films stick or break or both, whereupon they become stationary 15 and are ignited by the heat from the beam of light from the lamp, the result of which is that not only is damage done to the films and machines, but the risk of fire in places of entertainment and loss of life have to be guarded against, involving the setting up of elaborate and costly precautionary measures.

The main object of the invention, is therefore, to provide on picture projecting machines employing moving inflammable films, 25 safety means, whereby on a film becoming stationary, the beam of light is shut or cut off from the film, said means being so mounted and adjusted that in operating to bring about the above result, they cause the motor 30 driving the machine to be put out of action, thus rendering the machine inoperative and preventing the film from igniting.

According to the invention the safety means comprise a pivoted shutter adapted to 35 be set or held out of and clear of the beam of light by a catch at the end of the pivoted armature of an electric magnet. The shutter in its set position, closes separate spring contacts in the same circuit as the electromagnet, and in the same circuit as the motor 40 which drives the apparatus.

Also in the same circuit as the electromagnet, are a number of contacts which remain open so long as the film is feeding properly 45 and the machine is in proper running order.

Some of these contacts are located above the gate of the machine, and in the line of travel of the film as it passes from the feeding spool to the gate; others are located below the latter and in the line of travel of the film as it passes from the gate to the winding in spool, while one or more contacts are in the line of travel of the belt from the driving motor to the machine.

Should the film stick in the gate, or the

top loop flatten, or should said film or the driving belt break, a contact or contacts immediately closes and completes the electromagnet circuit, whereupon said magnet is energized and attracts its pivoted armature 60 which releases the shutter. Immediately this happens, the shutter, assisted by the spring contacts in the electromagnet and motor circuits, falls between the condensers and the gate thereby preventing the beam of light 65 from reaching the film. In falling, the shutter releases the spring contacts in the electromagnet and motor circuits, whereupon said contacts open and break both circuits.

Means are also provided whereby on 70 changing over from one machine to another, the setting or raising, of the shutter on one machine, causes the shutter on the other machine to drop. This is accomplished, by providing on each machine a contact located in 75 the same circuit as the electromagnet of the other machine, the setting or raising of each shutter closing a contact and completing the electromagnet circuit of the other machine.

The invention, will however, be more particularly described with reference to the accompanying drawing wherein:

Figure 1 shows in elevation a portion of a moving picture projecting machine fitted with the improvements.

Figure 2 is an enlarged sectional elevation showing the electromagnet and shutter contacts.

Figure 3 is a rear view of the plate carrying the shutter contacts.

Figure 4 is a part elevation of a centrifugal governor provided with means for closing the electromagnet circuit.

Figure 5 is a detail view of a contact for use either in conjunction with the film, or 95 the driving belt.

Figure 6 illustrates a contact for use in the loops of the film.

Figure 7 shows the mounting of a contact in conjunction with the driving belt, and 100 Figure 8 is a diagram illustrating the wiring.

The electromagnet 1 is housed in a casing 2, mounted over the condensers 1^a of the machine, and has a pivoted armature 3, the 105 outer end of which is formed into a catch 4.

The shutter 5 is hinged so as to be capable of dropping between the condensers 1^a and the gate 6 of the machine, for the purpose of preventing the beam of light from the 110

lamp, from reaching the film 7 as the latter passes through the gate 6. On the shutter 5 is provided a catch 5^a adapted to engage, when the shutter is raised, with the catch 4 of the armature 3, whereby the latter retains said shutter in its raised position against the pressure of spring operated plungers 8, 9 and 10.

These plungers 8, 9, 10 pass through a metal plate 11, and also through a plate 12 of insulating material, the plungers 8, 9 each having at their outer ends, buttons 8^a and 9^a of insulating material, and being pivotally connected at their inner ends to short levers 14-15 centrally pivoted on the plate 12.

The lower ends of the levers 14, 15 serve as switch blades, which when the shutter 5 is raised, make contact with plates 16, 17, respectively on the plate 12.

The contact plates 16 are located in the same circuit 18, (Figure 8) as the motor 25 which drives the machine, while the other pair of contact plates 17 is located in the same circuit 19 as the electromagnet 1.

The plunger 10 is made wholly of insulating material and has fixed thereon behind the plate 12 a metal collar 10^a having movement between said plate and a loop 13^a formed in a metal strip 13 on the rear of the plate 12. The collar 10^a is normally forced away from the loop 13^a, but when the shutter 5 is raised and presses against the plunger 10 it makes contact with the loop 13^a.

The metal strip 13 and the collar 10^a are located in the same circuit as the electromagnet of the other machine, that is when two machines are employed and connected, so that on raising the shutter 5 of one machine the circuit through the electromagnet of the other machine is closed, the shutter thereof dropped, and the machine put out of action.

At suitable points above and below the gate of the machine, rocker arms 20 are mounted. Each arm 20, Figure 5, carries at one end a roller 21 while its other end is formed into a switch blade capable of bridging contacts 22 located in the electromagnet circuit 19.

The film 7 is passed around these rollers 21, so that its tension when in running order keeps the switch ends of the arms 20 from entering the contacts 22. Should however from any reason the film 7 become slack at a point engaged by a roller 21, or leave the latter, said roller drops and allows the switch end of its arm 20 to enter and bridge its contacts 22, and complete the circuit 19 through the electromagnet 1 whereupon the latter is energized and attracts its armature 3.

The attraction of the armature 3 results in the catch 4 being lifted clear of the catch

5^a of the shutter 5. The latter thereupon immediately drops between the condensers 1^a and gate 6 and shuts off the beam of light from the latter.

The shutter 5 is assisted in its falling movement by the spring operated plungers 8, 9 and 10, which give an initial push to the shutter, and at the same time open the contacts 16 and 17, which results in both the motor circuit 18 and the electromagnet circuit 19 being opened, and the machine rendered inoperative.

Also the plunger 10 by its forward movement draws the metal collar 10^a from contact with the plate 13^a in the circuit of the electromagnet of the other machine.

Additional contacts comprising a pair of spring plates 23 also located in the same circuit 19 as the electromagnet 1, are placed in the upper loop 7^a of the film 7. These contact plates 23 normally remain apart, but should the loop 7^a straighten out more than the desired extent the plates 23 are forced together and close the electromagnet circuit 19 and cause the shutter 5 to drop and the circuits 18, 19 to be opened as before described.

Where it is impracticable to mount a rocker arm 20 in the lower loop 7^b of the film, a pair of spring contact plates similar to the plates 23 can be used, for the purpose of closing the electromagnet circuit 19 on the loop 7^b straightening out more than is desirable.

A rocker arm 20 is also used in conjunction with the driving belt 24, from the motor 25 so that should said belt break or leave its pulleys, the electromagnet circuit 19 is immediately closed, the shutter 5 is dropped, and the machine brought to a standstill.

Further means for bringing about the dropping of the shutter 5 so as to prevent the beam of light from reaching the film in the gate, should the running of the machine fall below normal, are also provided.

These means (Figure 4) consist in using the centrifugal governor at present fitted on existing machines, to keep the ordinary fire shutter (dispensed with in this invention) raised, for the purpose of keeping open contacts located in the electromagnet circuit 19, so long as the normal speed of running of the machine is maintained.

This governor 26 the construction of which is well known has connected to its arm 27, a hanging link 28, the upper end 29 of which carries an adjustable contact 30, while a further contact 31, which with the contact 30 is located in the electromagnet circuit 19, is also provided.

The arm 27 tends to fly outwards, and while the normal speed of the machine is maintained it forces the lower end of the link 28 outwards and the upper end 29 of the latter backwards, thereby keeping the

contacts 30—31 apart. Immediately however the speed of the machine falls below normal, the arm 27 drops and allows the upper end 29 of the link 28 to move towards the contact 31 so that the contact 30 will touch same and so close the electromagnet circuit 19.

Current for any of the circuits can be drawn from any suitable source.

10 What I do claim and desire to obtain by Letters Patent of the United States of America is:—

1. In a motion picture projecting machine, a shutter mounted so as to be capable of dropping between the condensers and the gate; an electromagnet having an armature provided with a catch for keeping the shutter raised; contacts controlled by the film and the machine driving belt for closing the electromagnet circuit; and contacts closed and allowed to open by the raising and dropping respectively of said shutter, for closing and breaking the motor and the electromagnet circuits.

25 2. In a motion picture projecting apparatus, a first machine, a pivoted shutter with a catch thereon; an electromagnet having a pivoted armature provided with a catch for engaging the catch of the shutter; contacts controlled by the film and the machine driving belt for closing the electromagnet circuit; a plurality of plungers connected to switch blade arms, springs for said plungers, the plungers being pressed against the action 30 of said springs by said shutter when raised, to make contact with plates in the motor and the electromagnet circuit; a second machine, and another plunger pressed against the action of another spring when the shutter is raised, for closing the electromagnet circuit of said second machine.

35 3. In a motion picture projecting machine, an electromagnet having an armature, a shutter, said armature holding said shutter raised, at times, contacts in the electrical circuit of the electromagnet, and located in a loop of film and adapted to be brought together by the straightening out of said loop.

40 4. In a motion picture projecting machine, a centrifugal governor, an arm connected therewith and having a pivoted link, an electric contact carried by said link, a fixed electrically connected contact; and an electromagnet having an armature adapted to retain a shutter out of the beam of light to the film, the circuit of said electromagnet including both of said contacts.

45 5. In a motion picture projecting machine, a motor, an electromagnet having a pivoted

armature with a catch thereon; a pivoted shutter with a catch thereon; spring operated plungers insulated from said shutter, levers connected with said plungers and having switch blades at their ends, a pair of contacts in the machine motor circuit, both mounted on an insulated plate, said switch blades and pairs of contacts, cooperating to regulate the machine.

6. In a motion picture projecting apparatus, a first machine, a motor for the same, an electromagnet having a pivoted armature with a catch thereon; a pivoted shutter with a catch thereon; a pair of spring operated plungers insulated from said shutter, and connected with separate levers having ends which act as switch blades; a pair of contacts in the electromagnet circuit and a pair of contacts in the machine motor circuit, both being mounted on an insulated plate, a second projecting machine, another spring operated plunger insulated from said shutter and carrying an electrically connected contact adapted to be moved against an electrically connected strip on said insulated plate, the contact on said plunger and said strip being both in an electromagnet circuit of said second machine.

7. In a motion picture projecting apparatus, a first machine, an electromagnet having an armature with a catch thereon; a shutter kept in a raised position by said catch, a second machine having an electromagnet, and a plunger operated by the raising of said shutter to close the electromagnet circuit of said second machine.

8. In a motion picture projecting apparatus, a first machine, an electromagnet having an armature with a catch thereon; a shutter kept in a raised position by said catch; a second machine having an electromagnet, and a spring pressed plunger associated with the first machine and carrying an electrically connected contact for closing the circuit of the electromagnet of the second machine.

9. In a motion picture projecting apparatus, a first machine, an electromagnet having a pivoted armature with a catch thereon; a hinged shutter adapted to be kept in a raised position by said catch, a second machine having an electromagnet, said shutter, when raised, closing the circuit of the electromagnet of said second machine.

Signed at city of Dunedin, in the Provincial District of Otago, Dominion of New Zealand, this 21st day of June 1921.

JOHN DALLAS LAW.
